(57) **CLAIM**

The ornamental design for a stand for electronic device, as
shown and described.

DESCRIPTION

FIG. 1 is a front elevational view of a stand for electronic
device showing my new design;

FIG. 2 is a rear elevational view thereof;

FIG. 3 is a right side elevational view thereof, a left side
elevational view thereof being a mirror image of the right side
elevational view;

FIG. 4 is a top plan view thereof;

FIG. 5 is a bottom plan view thereof;

FIG. 6 is an enlarged fragmental top perspective view of the
stand, taken along a line VI—VI of FIG. 3;

FIG. 7 is a rear and left side perspective view thereof; and,

FIG. 8 is an enlarged fragmental bottom perspective view of
the stand, taken along a line VIII—VIII of FIG. 3.
